G. M. JORDAN

ROOFING

Filed Sept. 4, 1923

INVENTOR.

Geo. M. Jordan,
BY
Winton S. Grandale,
ATTORNEYS.

UNITED STATES PATENT OFFICE.

GEORGE M. JORDAN, OF WINSIDE, NEBRASKA.

ROOFING.

Application filed September 4, 1923. Serial No. 880,672.

To all whom it may concern:

Be it known that I, GEORGE M. JORDAN, a citizen of the United States, and a resident of Winside, in the county of Wayne and State of Nebraska, have invented certain new and useful Improvements in Roofing, of which the following is a specification.

My present invention has for its primary object the production of an improved roofing, embodying shingles and sheet roofing, so constructed and associated as to insure a weather proof roof, which roofing covers a maximum area with a minimum weight, and in the laying of which the shingles are self-spacing.

Another object of the invention is the production of a roof of this class, wherein the major portion of the shingles are exposed to the weather, whereby the number of shingles required to cover a given area is reduced to the minimum.

Furthermore, the invention contemplates a roof of this class wherein the shingles are "blind-nailed" at both the top and the bottom, thereby preventing the wind from getting under the shingles. These and other objects and advantages I successfully attain in the embodiment hereinafter described, defined in the claim and illustrated in the accompanying drawings, which form a part of this application, and in which like characters of reference indicate corresponding parts throughout the several views, of which;

Fig. 1 is a fragmentary plan of a roof constructed in accordance with my invention.

Figure 2 is a transverse section thereof; and

Fig. 3 is an enlarged perspective view of one of the shingles and the associated strip of sheet roofing.

Referring, now, to the drawing, the sheathing of the roof, or its equivalent, is represented at 4. My improved roofing consists of strips of sheet material, preferably so called asphalt sheet roofing. The strips are laid horizontally, with the lower edge portion of each strip overlapping the upper edge portion of the next lower strip. The shingles, 6, are also made of sheet material, preferably asphalt sheet roofing, having stony particles imbedded in their faces to beautify them and render them fire proof. The lower edge portions of the shingles are folded under upon themselves, as at 7. Obviously the shingles are laid side by side in

rows; each row being associated with one of the lining strips, 5, and the under-turned portion, 7, of each shingle being inserted between the lower edge portion of the strip, 5, and the overlapped edge portion of the next lower strip, 5, as will be clearly understood from Fig. 2. The shingles and lining strips are held securely by nails, 8, driven thru the overlapping edge portion of the strip, 5, and the shingle portion, 7.

The method of laying the roofing preferably consists in first laying the lowermost strip, 5, across the roof and holding it in place by nailing at its upper edge portion as at 9, at suitable intervals. The first course of shingles is then laid on the said strip with the under-turned portions, 7, interposed between the lower edge portion of the said strip, 5, and the roof, 4, the said shingles and strip being so related that the lower edge of the strip, 5, extends to the fold of the shingle. The shingles are then lifted at their upper ends and the nails, 8, driven thru the said strip, 5, and the shingle portions, 7, and then into the roof, 4. The next strip, 5, is then laid with its lower edge portion overlapping the upper edge portion of the first mentioned strip the desired distance and the second course of shingles laid thereon with their under-turned portions, 7, interposed between the overlapping portion of the associated strips and the upper end portions of the next lower shingles, the upper ends of the shingles being then lifted and the nails, 8, driven thru the overlapping strip portion, the shingle portions, 7, and the overlapped portion of the next lower strip, 5. The laying of the strips and shingle courses is then continued until the entire roof is covered.

It will now be apparent that a roof thus constructed is weather-proof; that the shingles are "blind nailed" at both the top and bottom and that the major portion of the shingles being laid to the weather makes it possible to cover a maximum area with a minimum number of shingles and weight. And furthermore between the roof and the strips, 5, are dead-air spaces, 10, which make a warmer roof.

Altho I have illustrated and herein described the preferred embodiment of the invention, I would not be understood as being limited to such specific construction, for various alternations and modifications may be made in the details, and arrangements of

the parts herein disclosed without departing from the spirit and scope of the invention as defined in the attached claim, to wit;

The process of laying a roof, comprising
5 the laying of strips of roofing material the full length of the roof, overlapping the strips, the upper over the adjacent lower strip, temporarily tacking them in position, and covering them with shingles having
10 under-turned lips, the covering process comprising the inserting of the lips between the overlapped portions of the strips so that the shingles proper extend upwardly over the strips, bending the shingles back and

nailing underneath them through the overlapping portions of the adjacent strips, the upper edge of the lower adjacent shingles and the under-turned lips of the shingles which have been raised, then lowering the shingles and inserting their upper ends between the overlapping portions of the next adjacent pair of strips above, and then repeating the same operations with the next row of shingles.

In testimony whereof, I have hereunto 25 set my hand this 30th day of August, 1923.

GEORGE M. JORDAN.
